Edward Dryden, Bakersfield, and George Carlyle,
Long Beach, Calif.

Application July 22, 1944, Serial No. 114,520

Term of patent 14 years

(Cl. D31—4)

To all whom it may concern:

Be it known that we, Edward Dryden, a citizen of the United States, residing in Bakersfield, county of Kern and State of California, and George Carlyle, a citizen of the United States, residing in Long Beach, county of Los Angeles and State of California, have invented a new, original, and ornamental Design for a Fish Lure, of which the following is a specification, reference being had to the drawing forming part thereof.

In the drawing:

Figure 1 is a front elevational view of the fish lure showing our new design.

Figure 2 is a top plan view of the fish lure.

Figure 3 is a bottom plan view of the fish lure.

We claim:

The ornamental design for a fish lure, as shown.

EDWARD DRYDEN.
GEORGE CARLYLE.
